(57) **CLAIM**

The ornamental design for a cutting machine tool clamp, as shown and described.

DESCRIPTION

FIG. 1 is a front, right, top isometric view of a cutting machine tool clamp shown in an environment;

FIG. 2 a front, right, top isometric view of the cutting machine tool clamp with some portion of the environment omitted in order to clearly show aspects of the design;

FIG. 3 is front, left, top isometric view thereof;

FIG. 4 is a front elevation view thereof;

FIG. 5 is a left elevation view thereof;

FIG. 6 is a right elevation view thereof; and,

FIG. 7 is a top plan view thereof.

The broken lines in the figures indicate environmental subject matter and thus form no part of the claimed design.

1 Claim, 7 Drawing Sheets
